(57) **CLAIM**

The ornamental design for a bufferless 9mm upper assembly rifle receiver as shown and described.

DESCRIPTION

FIG. 1 is a perspective view of a bufferless 9mm upper assembly rifle receiver showing my new design;

FIG. 2 is a side view of the bufferless 9mm upper assembly rifle receiver;

FIG. 3 is a top view thereof;

FIG. 4 is a perspective view of a bolt assembly mechanism of the bufferless 9mm upper assembly rifle receiver and certain internal components;

FIG. 5 is a top view thereof;

FIG. 6 is a bottom view thereof;

FIG. 7 is a first side view thereof;

FIG. 8 is a second side view thereof;

FIG. 9 is a front view thereof; and,

FIG. 10 is a back view thereof.
